UNITED STATES PATENT OFFICE.

WILLIAM J. CONNELL, OF HUNTINGTON, WEST VIRGINIA.

CHECK LOCK.

Application filed February 25, 1922. Serial No. 539,221.

To all whom it may concern:

Be it known that I, WILLIAM J. CONNELL, a citizen of the United States, residing at Huntington, in the county of Cabell and State of West Virginia, have invented new and useful Improvements in Check Locks, of which the following is a specification.

As is well known, account of miners' work in loading cars is made by checks. These checks are attached to the cars at the loading point and are removed therefrom at the tipple. A comparatively great number of contrivances have been employed for holding the check on the car when the latter is in transit, a number of which automatically eject the check at the tipple. Regardless of such check holding means, it has been found that in a number of instances the checks have been lost or fraudulently removed, so that the miner does not receive recompense for work actually done.

It is the object of the present invention to produce a means for locking a check on a mining car in a manner whereby the same positively cannot be removed as long as the car is loaded.

It is a further object to produce a check lock for mining cars in which the check is in the nature of a key that is inserted in the barrel of a lock which is attached to the car and when arranged in the barrel and turned with the barrel, means is operated to arrange the same either in contacting engagement with the load in the car or in contacting engagement with the frame for the running gear of the car to prevent the turning of the barrel, and consequently the removal of the key from the barrel as long as the load is in the car or the car is in position to receive the load, and whereby the barrel and key can only be turned when the car is tilted to dumping position.

The foregoing, and other objects which will appear as the nature of the invention is better understood, may be accomplished by a construction, combination and operative association of parts such as is disclosed by the drawings which accompany and which form part of this specification.

50 In the drawings:—

Figure 1 is a side elevation of a miner's coal car illustrating the application of the improvement.

Figure 2 is a sectional view on the line 2-2 of Figure 1, on an enlarged scale.

Figure 3 is a sectional view substantially

similar to Figure 2, but showing the car in dumping position to permit of the removal of the key from the lock barrel.

Figure 4 is a sectional perspective view of the lock casing.

Figure 5 is a similar view of the barrel and the head which is attached thereto.

Figure 6 is a view of the key which provides a check.

Figure 7 is a view illustrating the manner in which the barrel or tumbler of the lock is turned to key retaining position when the body of the car is in load receiving position.

A mining car, of the usual construction, is illustrated in the drawings, and is indicated by the numeral 1. Through one side of the car, adjacent to the bottom thereof, I bore a round hole, and through this hole I insert the tubular body 2 of a lock casing. The body has threadedly secured to its outer edge a face plate 3, the latter having passed therethrough screws which enter the side of the car. The face plate 3 has a central opening therethrough which is in registering alignment with the bore of the cylindrical lock casing, but which projects a slight but suitable distance into the bore, thus providing the inner wall of the face plate with a shoulder. The cylindrical casing 2, adjacent to its outer end is provided with an inwardly directed annular flange 4. The bore of the casing 2, at a suitable distance away from the face plate 3 is provided with a substantially semi-cylindrical groove 5, and with a longitudinal slot 6 that communicates with the groove and also passes through the face plate 1.

The turnable member or barrel of the lock is indicated by the numeral 7, the same having a reduced extension whereby the barrel proper is in contact with the shoulders provided on the inner face of the face plate and the annular rib on the inner end of the casing. The reduced extension of the barrel is indicated by the numeral 8 and extends through the casing. The extension 8 has on its end a laterally extending head 9.

The barrel 7 from its outer end is provided with a longitudinal slot 10.

The key, which also provides the check is indicated by the numeral 11, the said key having an opening or other identification mark or character thereon and having a bit 12 projecting from one edge thereof, the said bit, when the key is passed through the key

hole opening in the face plate, casing and barrel being arranged in alignment with the semi-cylindrical groove in the casing so that when the key is turned and the barrel 5 revolved the head 8 will be in a position to be contacted by the load in the car and the weight of such load will prevent the accidental turning of the barrel to release the key from the lock.

10 As soon as the load is dumped, it will be apparent that the barrel can be turned to permit of the key or check being removed from the lock.

15 In Figure 7 of the drawings, there is illustrated the lock positioned so that the head of the barrel or tumbler will contact with the frame of the car when the latter is in normal load receiving position, and by virtue of such contact the barrel is turned to 20 hold the key between the barrel and lock casing.

It is thought that the foregoing description, when taken in connection with the drawings will fully set forth the simplicity 25 of the construction and the advantages of the improvement to those skilled in the art to which such inventions relate.

Having described the invention, I claim:—
In combination with a dump car, of means

for locking a check key thereto, comprising 30 a cylindrical casing received through one side of the car, an annular flange formed with the casing adjacent to its inner end, a face plate threadedly secured to its outer end, and having a notched opening registering with the bore of said casing but being of less area than that of said bore, a barrel received in the casing having an inner reduced end projecting through the inner end of the casing and being provided with a longitudinal slot 40 designed to register with the notch when the barrel is in one position, a laterally extending head carried by the projecting end of the barrel, said casing being provided with a semi-circular groove which 45 communicates with a longitudinal slot entering from the outer end thereof and said slot being aligned with the notch in the face plate whereby a key may be inserted through the notch, the longitudinal slot of the casing and the slot of the barrel respectively 50 to turn the lateral extending head through the medium of the barrel to a position to be contacted by the load in the car, as and for the purpose specified.

55 In testimony whereof I affix my signature.

WILLIAM J. CONNELL.
